(57) **CLAIM**

The ornamental design for an ergonomic spinning reel, as shown and described.

DESCRIPTION

FIG. 1 is a perspective view of an ergonomic spinning reel, showing my new design;

FIG. 2 is a front perspective view thereof;

FIG. 3 is a left-side elevational view thereof;

FIG. 4 is a right-side elevational view thereof;

FIG. 5 is a rear elevational view thereof;

FIG. 6 is a front elevational view thereof;

FIG. 7 is a top plan view thereof;

FIG. 8 is a bottom plan view thereof; and,

FIG. 9 is a bottom perspective view thereof.

The broken lines showing a fishing pole and a spool of fishing line depict environmental matter that forms no part of the claimed design. The remaining broken lines in the figures depict portions of the ergonomic spinning reel that form no part of the claimed design.

1 Claim, 9 Drawing Sheets
